(57) **CLAIM**

The ornamental design for a medication container dock, as shown and described.

DESCRIPTION

FIG. 1 is a top perspective view of a medication container dock in accordance with our new design;

FIG. 2 is a left view of FIG. 1;

FIG. 3 is a right view of FIG. 1;

FIG. 4 is a top view of FIG. 1;

FIG. 5 is a bottom view of FIG. 1;

FIG. 6 is a top perspective view of a medication container dock in accordance with our new design;

FIG. 7 is a left view of FIG. 6;

FIG. 8 is a right view of FIG. 6;

FIG. 9 is a top view of FIG. 6; and,

FIG. 10 is a bottom view of FIG. 6.

The broken lines in the drawings illustrate portions of the medication container dock that form no part of the claimed design.

1 Claim, 9 Drawing Sheets
